UNITED STATES PATENT OFFICE.

CHARLES M. BOWMAN, OF LEBANON, PENNSYLVANIA.

MACHINE FOR MAKING MATCHES.

SPECIFICATION forming part of Letters Patent No. 499,777, dated June 20, 1893.

Original application filed January 26, 1893. Serial No. 459,833. Divided and this application filed April 3, 1893. Serial No. 468,906. (No model.)

To all whom it may concern:

Be it known that I, CHARLES M. BOWMAN, a citizen of the United States, residing at Lebanon, in the county of Lebanon and State of Pennsylvania, have invented certain new and useful Improvements in Machines for Making Matches; and I do hereby declare the following to be a full, clear, and exact description of the invention, such as will enable others skilled in the art to which it appertains to make and use the same.

My present invention relates to friction-matches and has for its object certain improvements in machines for making this class of matches economically.

The invention will be fully disclosed in the following specification and claims.

In the accompanying drawings which form part of this specification, Figure 1, represents a rear elevation of my improved machine for making matches; Fig. 2, an end elevation of the same; Fig. 3, a vertical transverse section; Fig. 4, an enlarged sectional view of part of the fulminate depositing drum; Fig. 5, a transverse section of the same; and Fig. 6, a top plan view of section of a sheet of matches, the product of the machine.

Reference being had to the drawings and the letters thereon A. A. indicates the two ends of the frame of the machine, upon which the several parts are supported, and are connected by longitudinal bars a. b. c.

B, is the fulminate receptacle provided with a jacket d to form a chamber e for steam or hot water to heat the fulminate and maintain it in a semi-liquid or plastic condition and is detachably supported between the ends of the frame.

Within the fulminate receptacle are two pulleys g. h. supported upon shafts i k, to the latter of which motion is communicated by a gear wheel l, and upon said pulleys is supported a flexible fulminate conveyer C.

In the upper part of the receptacle B, and extending across the same is a scraper m to regulate the quantity of fulminate presented to the fulminate depositors, and may be adjusted in the usual manner of adjusting analogous devices.

D is a fulminate-depositing drum mounted upon a shaft n supported on brackets o p, and is revolved by a gear wheel q which meshes

with a gear wheel r attached to the shaft s upon which the drum E is supported.

In the drum D are longitudinal grooves t 55 in which are inserted bars u provided with a number of chambers v to receive fulminate and deposit it upon the paper of which the matches are made. The grooves t are equidistant in the periphery of the drum, the space 60 between them being equal to the length of the matches to insure the depositing of the fulminate near one end and on one side of the matches. Each chamber v terminates in a cylindrical nozzle w and is provided with a 65 piston or plunger y attached to a bar z so that all the pistons of each bar u are operated synchronously to draw in and eject the fulminate at the proper time in the revolution of the drum D. On the ends of the bar z are friction rollers 70 a' which travel in grooves b' b' on the inside of the heads c' c' which are separate from the body of the drum and are stationary. The grooves are provided with a raised part d', as shown in Fig. 3, which commences at a point 75 e' just below the center of the axis of the drum to raise the pistons y when the fulminate chambers or receptacles are in a vertical position to draw up fulminate from the conveyer C, and terminates at the point f', to deposit 80 the fulminate when the ends of the nozzles w are brought into contact with the upper side or surface of the paper as it passes over the drum E. The pistons y are retracted just sufficient to draw into the chambers or receptacles v a drop of fulminate large enough to serve to ignite the matches. When the rollers a' strike the projections e' in the grooves b' b', the fulminate is carried in the chambers v until the rollers reach the end of the raised 90 portion of the track at f', when as the rollers descend from said raised portion the plungers are forced down and quickly expel the fulminate upon the paper.

By reference to Fig. 3, it will be observed 95 that four of the bars z operate in slots g' in the arms h' of the drum D. The paper in the roll F is placed on a shaft i' which is supported in the ends A. A. of the frame so that the roll can be readily inserted, and the paper 100 is passed under the drum G and between it and the drum H, which two drums constitute the feed mechanism for the paper by frictional contact. The drum H is provided on

its peripheral surface with concentric cutting edges k' which cut or puncture the paper lengthwise to form a fragile connection between the contiguous sides of the matches, 5 and with longitudinal cutting edges l' which in like manner sever the paper transversely and form a fragile connection between the contiguous ends of the matches. The paper thus cut or perforated is readily separated 10 when it is desired to pull or break off a match from the sheet or card.

The drum G is revolved by a gear wheel m' which meshes with the wheel n' attached to the shaft of the drum H, and it is connected 15 to the wheel r by the pinion o' so that all the revolving parts of the machine operate in unison.

Power may be applied to the machine in any approved manner by supplying a suitable 20 pulley to be attached to one of the shafts supporting the gear wheels.

After leaving the drum E, the sheet I is properly divided into matches p' , and each match provided with a drop q' of fulminate passes 25 over a revoluble drum K and is again rolled after having traveled a sufficient distance to allow the fulminate on the match to dry.

The paper may be of any kind suitable for the purpose, manila or straw being preferred, 30 and is of a thickness sufficient to give body to the match, and is first prepared by saturating the paper with a suitable inflammable material such as paraffine, wax or their equivalents until the paper has become thoroughly 35 impregnated, after which it is dried and is then rolled, when it is ready to be converted into matches. Paper thus treated burns steadily and is not easily extinguished by currents of air.

40 It has heretofore been proposed to print matches, by providing a cylinder with small projections on its periphery and immersing or dipping said projections in fulminate and pressing the projections against the lower surface of a sheet of paper to print the fulminate on the paper of which the matches are formed. In such a construction the fulminate is liable 45 to gravitate off the ends of the projections before they reach the paper and as a consequence no deposit of fulminate on the paper can be relied upon. In contradistinction to such a construction and procedure, I convey 50 the fulminate in suitable chambers or receivers and at intervals drop or deposit the fulminate on the upper side of the paper as it is being fed through the machine and thereby secure the proper quantity of fulminate to each match to insure ignition.

Having thus fully described my invention, 60 what I claim is—

1. In a machine for making matches, the combination of a fulminate-receptacle, chambers or plungers for raising, conveying and expelling fulminate in drops, and means for feeding paper.

65 2. In a machine for making matches, the combination of a fulminate-receptacle, a ful-

minate conveyer, chambers or plungers for raising, conveying and expelling fulminate in drops and means for feeding paper. 70

3. In a machine for making matches, the combination of a fulminate-receptacle an endless conveyer in said receptacle, a drum provided with chambers or plungers for receiving, conveying and depositing fulminate, and 75 means for feeding paper.

4. In a machine for making matches, the combination of a fulminate-receptacle, a fulminate-conveyer, a drum provided with fulminate chambers supported above said receptacle and conveyer, and a suitable support for 80 a sheet of paper below said drum.

5. In a machine for making matches, the combination of a fulminate-receptacle, a drum provided with a plurality of fulminate chambers and plungers, arranged equidistant in the periphery of the drum, a fulminate conveyer below the drum and means for feeding paper. 85

6. In a machine for making matches, the combination of a fulminate-receptacle, a heating chamber for said receptacle, a conveyer within the receptacle a plurality of fulminate chambers and plungers, revolvably supported above said conveyer, and means for feeding 90 paper.

7. In a machine for making matches, the combination of means for puncturing paper longitudinally and transversely at the contiguous edges and ends of the matches, a fulminate receptacle, a plurality of fulminate chambers and plungers, and means for feeding paper. 100

8. In a machine for making matches, the combination of means for feeding paper, 105 means for puncturing the paper at the contiguous edges and ends of the matches, a fulminate-receptacle and a plurality of fulminate chambers provided with plungers.

9. In a machine for making matches, the combination of means for puncturing paper, a fulminate-receptacle, a revoluble drum provided with a plurality of fulminate chambers and plungers a revoluble support for paper while the fulminate is being deposited thereon, and means for feeding paper. 115

10. In a machine for making matches, the combination of a fulminate-receptacle, a fulminate-conveyer, means for puncturing paper, a plurality of chambers provided with plungers for raising conveying and depositing fulminate in predetermined quantities, and means for feeding paper. 120

11. In a machine for making matches, the combination of a fulminate-receptacle, a drum 125 provided with a plurality of bars having chambers therein, bars supporting plungers for said chambers and engaging grooves in the heads of the drum and means for retracting and projecting said plungers.

12. In a machine for making matches, the combination of a fulminate-receptacle, a revoluble drum supporting a plurality of bars provided with chambers, bars supporting 130

plungers for said chambers within said drum, and stationary heads for the drum provided with grooves with which the ends of said plunger-bars engage.

5 13. In a machine for making matches, a fulminate depositor consisting of a plurality of chambers provided with plungers, and means for retracting the plungers a fulminate conveyer to raise fulminate and means for protecting the plungers to expel the fulminate from the conveyer.

14. In a machine for making matches, a fulminate-depositor consisting of a drum provided with a plurality of grooves, bars having chambers therein and supported in said grooves, and plungers for expelling fulminate.

In testimony whereof I affix my signature in presence of two witnesses.

CHARLES M. BOWMAN.
